UNITED STATES PATENT OFFICE.

JAMES T. Langley, of Portland, and EDWIN THOMAS, of La Grande, Oregon.

GLOBE-VALVE.

1,114,995.

Specification of Letters Patent.

Patented Oct. 27, 1914.

Application filed July 24, 1913. Serial No. 780,924.

To all whom it may concern:

Be it known that we, JAMES T. Langley and EDWIN THOMAS, citizens of the United States, the former residing at Portland, in the county of Multnomah, the latter at La Grande, in the county of Union, both in the State of Oregon, have jointly invented a new and useful Improvement in Globe-Valves, of which the following is a specification, reference being had to the accompanying drawings.

Our invention relates to a class of valves used for general purposes and particularly in and with boilers and steam heaters.

The object of our invention is to provide a valve of the globe type in which the valve can be ground in its seat without removing the valve, also wherein a seat is formed above the valve, to prevent any leakage about the valve stem while the valve is being packed.

Our device is simple, cheap, and can be applied in any valve.

We attain the objects stated, as well as other advantages, by the construction, combination and arrangement of parts, illustrated in the accompanying drawing, which forms a part hereof.

The figure in our drawing illustrates a valve of the globe type, and our invention will now be more particularly described in connection with the figure shown. This figure is a vertical section through the center of the device.

As illustrated, 1 indicates, as a whole, a valve casing or shell. It is divided by a diaphragm 2, into chambers 3 and 4. The chamber 3 communicates with the outlet port 5, and the chamber 4 with the inlet port 6 of said valve. The diaphragm 2 is provided with a centrally disposed opening or passage 7. In the upper part of this passage is formed a valve seat 8, which is adapted to receive a valve. A neck 9 is formed in the upper part of the casing 1. The neck is externally threaded with a thread 10. A nut 11, provided with an internal thread, is adapted to be received on the neck 9. The nut 11 has a vertical opening 12 through its top. A vertical gland 13 is placed within the neck 9. The gland 13 has a circular shoulder 14 near its lower end adapted to engage the upper end of the neck 9 and the top of the nut 11.

The upper end of the gland 13 is exter-

nally threaded. An internally threaded packing nut 15 is secured on the upper end of the gland 13. The gland 13 is also formed with an internal thread 16 in its upper part, and is adapted to receive a threaded valve spindle. Below the thread 16 the gland is formed with a larger vertical passage 17. The lower end of the gland 13 is also formed with a valve seat 17.

The valve spindle 18 as a whole, comprises two members 19 and 19'. The member 19 has a cylindrical part 20 on its lower end, which part is adapted to be received within the gland passage 17. Above the part 20 the member 19 has an external thread 21 adapted to be received by the thread 16. The cylindrical part 20 has a female part 22 of a T-joint near its upper end. Extending from the part 22 the cylindrical part 20 is formed with a vertical slot 23 extending through its sides. On the upper end of the member 19 is an operating device consisting of an ordinary hand-wheel 24.

The member 19' has a flat central part 25 adapted to be received within the slot 23. The edges of the flat central part of the member 19' are flush with the sides of the cylindrical part. On the upper end of the member 19' is formed the male part 26 of a T-joint, the same being adapted to be received within the female part 22 of the member 19. The male part 25 is of suitably lesser dimension vertically than the female part 22 of the T-joint. On the lower end of the member 19' there is formed a valve 27 adapted to be received in the valve seat 8. The valve is also beveled on its upper side so it may be received in the upper seat 17' of the gland 13. The direction of the flow of fluid is indicated by arrows.

It will now be seen that when the parts of our device are assembled and the valve is in position as shown in the drawing, the inlet port is closed, by reason of the valve 27 being in its lower seat. Upon operating the hand-wheel 24 to open or close the valve it is first rotated in its seat, thus grinding it in place, before it leaves the seat. This is accomplished by reason of the T-joint, the male part being of less dimension, so allowing for a suitable play in the joint. It will be further observed that in our device we have provided an upper seat in the gland and that the valve can be held

therein. When the valve is in the upper seat, it will be observed that the packing nut may be removed, in order to repack, without shutting off the flow of fluid through the shell.

Having thus described our device we claim:

1. A valve, comprising a shell provided with a diaphragm forming two compartments respectively communicating with the inlet and outlet of the valve, said diaphragm having a centrally disposed horizontal portion provided with an opening with a valve seat surrounding it on the upper side of the diaphragm, a vertical shell neck above the valve seat, a gland securable on the shell neck internally threaded near its upper end and having a continuous vertical cylindrical passage below the threaded part, a valve spindle within the gland composed of an upper vertical member threaded near its central part, its lower part being cylindrical with a vertical slot extending through the sides of the same and with the female part of a T-joint in the upper end of said slot, also a lower member comprising a flat central part which extends through the slot and the edges of which are flush with the cylindrical part of said spindle, a valve on the lower end of said central part formed to adapt it to be received in the aforesaid upper and lower valve seats, also the male part of a T-joint in the upper end of said central part of lesser vertical dimension than the aforesaid female part,

and means to operate the spindle, substantially as described.

2. A valve, comprising a shell provided with a diaphragm forming two compartments respectively communicating with the inlet and outlet of the valve, said diaphragm having a centrally disposed horizontal portion provided with an opening with a valve seat surrounding it on the upper side of the diaphragm, a vertical shell neck above the valve seat, a gland securable on the shell neck internally threaded near its upper end and having a continuous vertical cylindrical passage below the threaded part, a valve spindle within the gland composed of an upper vertical member threaded near its central part, its lower part being cylindrical with a vertical slot extending through the sides of the same and with the female part of a T-joint in the upper end of said slot, also a lower member comprising a flat central part which extends through the slot and the edges of which are flush with the cylindrical part of said spindle, a valve on the lower end of said central part formed to adapt it to be received in the aforesaid valve seat, also the male part of a T-joint in the upper end of said central part of lesser vertical dimension than the aforesaid female part, and means to operate the spindle, substantially as described.

JAMES T. LANGLEY.
